FILLING HEAD HAVING OVERFLOW VALVE
CHECK MEANSCarl L. Day and James E. Freeze, Baltimore, Md.,
assignors to Crown Cork & Seal Company, Inc.,
Baltimore, Md., a corporation of New York

Application January 26, 1950, Serial No. 140,572

1 Claim. (Cl. 226—114)

1

The present invention relates to filling heads for use on counterpressure beverage fillers.

In the filling of carbonated beverages, it is usual to provide a filling reservoir containing a body of carbonated liquid together with a body of gas above the liquid. Bottles or other containers are filled from the reservoir by first operating the filling head valve to establish counterpressure in the bottle, *viz.*, a pressure corresponding to that existing in the reservoir above the liquid. Then the valve is operated to cause liquid to flow into the bottle while the counterpressure is returned to the reservoir, the liquid rising in the bottle until it covers the counterpressure escape port. At that moment, the filling head valve should be operated to stop liquid flow and counterpressure return.

Rotary filling machines may have as many as fifty filling heads. Even if all of the filling head passages are carefully machined to exact measurements, flow of liquid through some of the filling heads is very apt to be slower than through others. However, in order to prevent "short" filling, the filling head valve trip which operates the valves to stop liquid flow must be so positioned that it will accommodate the slowest flowing filling head of the machine. This results in making it possible for bottles beneath the faster flowing filling heads to become filled to the proper point before the valve is operated to stop liquid flow. Surplus liquid flowed into such bottles will rise in the counterpressure return passage of the filling head.

Any liquid which rises in the counterpressure return passage will be blown into the bottle next placed beneath such filling head and, more particularly, when the filling head is operated to produce counterpressure flow into such next bottle. If any substantial amount of liquid is thus blown into an empty bottle or a bottle containing a charge of syrup, foaming will be initiated which may interfere with filling of the bottle. In order to avoid this, it has been proposed to provide filling machines with relatively expensive equipment to blow liquid from the counterpressure return passage of each filling head intermediate each filling cycle.

An object of the present invention is to provide a filling head including means to limit the rise of liquid in the counterpressure return passage.

Another object of the invention is to provide means of the above character and which is of such design that it readily can be incorporated in a filling head of the rotary disc valve type.

2

Other objects and advantages of the invention will be apparent from the following specification and attached drawings wherein:

5 Figure 1 is a side elevation, partly in vertical section, of a filling head, the filling head being illustrated attached to the filling reservoir support of a filling machine and the support being shown in radial section.

10 Figure 2 is an elevation of the seat face of a filling head body element, portions being in section.

Figure 3 is an enlarged detail view of a retaining means mounted in a counterpressure return passage, and

15 Figure 4 is a top plan view of the retaining means of Figure 3.

The filling head 6 illustrated in the drawings is of the general construction disclosed in George J. Huntley and Robert J. Stewart Patent No. 2,145,765, issued January 31, 1939, for Filling Machine. Hence, filling head 6 includes a body element 7 provided with a seat face 8. Also, a central stud 10 projects from seat face 8 and a disc valve 12 rotates about stud 10 to control flow 20 through the filling head. Body element 7 is secured to the periphery of a flange 14 extending outwardly from the usual filling reservoir. As is customary in rotary filling machines for beverages, the filling reservoir rotates above and with a table including bottle supporting platforms which are vertically reciprocable in alignment with the nozzles of the filling head. Also, the filling reservoir will include valve arrangements to insure that the level of the liquid in the reservoir will be substantially constant and that a body of gas at suitable pressure will be maintained above the surface of the liquid.

As is best shown in Figure 2, body element 7 is provided with a plurality of passages extending horizontally therethrough from its rear face 16 to its seat face 8, these passages including gas passages 20 and 22 and a liquid passage 24. The gas passages 20 and 22 are connected to the upper portion of the reservoir by piping 23. Body element 7 also has a passage 26 extending from its seat face 8 to its lower face 27, *viz.*, its face which carries the filling nozzle 28. The rotatable disc valve 12 of the filling head is provided with a passage 32 which is adapted to connect the passage 26 with the passage 20 as hereinafter described. Disc valve 12 also includes the usual passages, not shown, adapted to connect the liquid passage 24 with a passage 34 in the valve body element and which terminates in a port 36 (Figure 1) located centrally of the lower face 27.

In accordance with the arrangements of the above-mentioned Huntley and Stewart patent, the body element 7 also will be provided with a snift passage 38 adapted to open to a bottle sealed to the filling nozzle. A snift passage 40 is also provided to open to a snift exhaust fitting 42. Disc valve 12 will include passages to connect the liquid passages 24 and 34 as well as a passage to connect the body element snift passages 38 and 40.

The filling head body element 7 includes a downwardly extending threaded boss 44 which terminates in the above-mentioned lower face 27 of the filling head. Face 27 is provided with a central recess 48 in which the upper end of the filling nozzle 28 is fitted. Port 36 of liquid passage 34 opens to recess 48 to thereby be in communication with the central liquid passage 52 of the filling nozzle. Nozzle 28 includes a flange at its upper end which fits in recess 48 and rests upon a collar 54 bearing against the lower face 27 of body element 7. Collar 54 is held in position against the face 46 by a ring-nut 49 threaded upon boss 44. Collar 54 includes a passage 56 enlarged at its upper end to receive a small sleeve 58, the passage then being inclined toward filling nozzle 28 to communicate with a groove 60 formed in the periphery of the nozzle. As is described in the above-mentioned Huntley and Stewart patent, a sleeve 62 surrounds filling nozzle 28 to close the outer portion of groove 60 and thereby form the gas passage of the filling nozzle. A bottle centering bell 63 is vertically slidable upon the filling nozzle as is described in said Huntley and Stewart patent.

It will be understood that all of the structure described above is usual and that disc valve 12 will be rotated upon stud 10 by trips spaced about the path of travel of the filling heads with the filling reservoir and filling table. These trips will successively contact with the operating arms 64 and 65 of valve 12 to first cause the gas passages 20 and 22 to be brought into communication with the gas passage 26 so that gas above the liquid in the filling reservoir will flow into the bottle through filling nozzle groove 60 to thereby establish the same pressure in the bottle that exists above the liquid in the reservoir. Then disc valve 12 will be operated to cause liquid passages 24 and 34 to be brought into communication so that liquid will flow from the filling reservoir and downwardly into the bottle through the liquid passage 52 of nozzle 28. During this position of disc valve 12, body element passage 26 will be in communication with passage 20 so that gas and air will move from the bottle through nozzle groove or passage 60, passage 56 of collar 54 and thence by passage 26 of body element 7, passage 32 of disc valve 12, passage 20 of the body element, and thence by pipe 23 to the upper portion of the filling reservoir.

In order to prevent an undue amount of liquid from rising in the just-described gas return passages in the event that liquid continues to flow into the bottle after the liquid has covered the lower end 66 of the filling nozzle gas passage 60, the invention involves the provision of the following float check valve arrangement in body element 7. Gas passage 26 is counterbored from its face 27 to form a chamber 70 terminating in a valve seat 72. The lower end of chamber 70 is threaded as indicated at 74. A float valve 76 is positioned in chamber 70, valve 76 preferably being solid and formed of a plastic material lighter than water. The upper end of float valve 76 is of

frusto-conical form as indicated at 78 so that it will form a seal against the valve seat 72. The lower end of float 76 may be rounded to a central flat portion 80 of sufficient area that the float 5 valve will tend to stand upright upon a retaining collar 82 threaded into the lower portion of chamber 70. It will be observed that float 76 is of smaller diameter than the bore of chamber 70 to thereby provide an annular flow path between the surface of the float valve and the chamber wall, this flow path having the same cross-sectional area as the passages 28 and 56.

As is best shown in Figures 3 and 4, the retaining collar 82 includes a central bore 84 which is adapted to receive the sleeve 58 of collar 54 and the upper end of bore 84 is reduced to have the same diameter as the passages 28 and 56. At its upper end, collar 82 is diametrically notched as indicated at 86 along lines approximately 60° apart, the notches thereby forming upwardly faceted projections 88 upon which the float valve 76 will rest when the float valve is in lowered position. The notches 86 are of sufficient size and depth to permit a flow therethrough of the same 20 volume as is accommodated by the passages 28 and 56.

Float valve 76 will remain in the lowered position of Figure 2 during downward flow of gas through the gas passages. Also, under normal 30 gas return conditions, float valve 76 will remain lowered. When valve 76 is in its lowered position, gas will move past the valve without restriction. In the event that liquid in the bottle beneath the filling head rises to close the port 66 35 and thereafter continues to rise in the gas return passages before the disc valve 12 is moved to stop liquid flow and gas return, valve 76 will prevent liquid from rising above valve chamber 70. That is, if the liquid rises in the gas return 40 passages to such an extent as to fill chamber 70, valve 76 will float upwardly so that its upper end will seal against the seat 72 of the chamber. Therefore, the quantity of water which can move onto the gas return passages will be a minimum. Without the provision of the chamber 70 and valve 76, the liquid could rise through the filling 45 head and into the pipe 23 to the same level as the level of the liquid in the reservoir, viz., to a point above the passage 20. It will be understood that such an extreme rise of liquid could only occur in the case of filling heads which are in filling position at the time that operation of the machine is stopped for some reason.

After headspace pressure has been snifted from the bottle and the bottle lowered from filling nozzle 28, the liquid which has flowed into passage 60 will remain therein because the passage is of small cross-section. When a new bottle is placed in sealed relation with the filling head and disc valve 12 operated to counter-pressure position, the downward flow of gas through passage 28 will move all of the liquid out of chamber 70 and the portion of the passage below that chamber. However, this portion of the passage is of sufficiently small cross-section and length that it will not receive and hold more than about three cubic centimeters. Furthermore, because the liquid will be directed from the nozzle against the side wall of the bottle, liquid will simply flow downwardly along the bottle and no foaming will result.

The provision of the above-mentioned float check valve arrangement in the filling head avoids the necessity of providing the machine 75 with any means to blow out the counterpressure

return passages of a filling head during the time that no bottle is positioned beneath the head. Such equipment is comparatively expensive compared to the cost of the simple machining operation and the cost of parts involved by use of the present invention. In more detail, the provision of the float chamber 70 opening to the lower face 27 of body element 7 permits the invention to be provided at minimum expense upon filling heads of standard and well-known type.

The terminology used in the specification is for the purpose of description and not of limitation, the scope of the invention being defined in the claim.

We claim:

In a filling head for counterpressure fillers, a body element including a seat face and a face adapted to be secured to a filling machine reservoir, said body element including a first liquid passage and a first gas passage extending between said faces and respectively adapted to be connected at said second-named face to the liquid and gas containing portions of the reservoir, said body element including a third face lying substantially normal to said seat face and a second liquid and a second gas passage extending between said seat face and said third face, said second gas passage including a leg extending normal to said third face, a disc valve rotatable on said seat face and provided with flow passages to connect the two liquid passages and the two gas passages, a filling nozzle normal to said third face and including a liquid passage in communication at said third face with the second

liquid passage of said body element, said nozzle including a gas passage, a collar surrounding said nozzle adjacent said third face and including a passage to connect the nozzle gas passage and the second gas passage of said body element, the leg of said second gas passage of said body element which is normal to said third face being enlarged inwardly from said third face to a point spaced from said third face and the inner end of such enlarged passage portion being provided with a valve seat, a float valve in said enlarged passage portion, and means in the outer portion of the enlarged passage portion to limit movement of said float valve away from

10
